JOHN DREXLER Inventor

By his Attorney

Oscar Guier

UNITED STATES PATENT OFFICE.

JOHN DREXLER, OF TOLEDO, OHIO.

FIELD-BED.

1,257,984.

Specification of Letters Patent.

Patented Mar. 5, 1918.

Application filed November 17, 1917. Serial No. 202,457.

To all whom it may concern:

Be it known that I, JOHN DREXLER, a subject of the King of Hungary, resident of Toledo, county of Lucas and State of Ohio, 5 have invented certain new and useful Improvements in Field-Beds, of which the following is a specification.

This invention relates to improvements in hammocks or portable beds and has as its 10 special object the provision of a bed particularly adapted for field service and which can be quickly erected and adjusted affording a comfortable bed.

Other objects of the invention are to provide 15 a hammock or bed of a type which may be readily transported and which may be erected in an easy and expeditious manner or collapsed and rolled for transportation as desired.

20 This and other like objects are attained by the novel construction and combination of parts hereinafter described and shown in the accompanying drawings, forming a material part of this specification, and in 25 which—

Figure 1 is a perspective view showing a hammock made in accordance with the invention.

Fig. 2 is a perspective view of a preferred 30 form of a mattress used in connection with the invention.

Fig. 3 is a perspective view showing a detail of construction.

Fig. 4 is a fragmental perspective view 35 showing the construction of the frame support.

Fig. 5 is a side elevational view of a hammock together with its support as made in conformity with the invention.

40 Fig. 6 is a top plan view of the same, parts being broken away and the cover turned down to disclose the interior.

Fig. 7 is a fragmental side elevational view of the hammock support, and

45 Fig. 8 is a view of the hammock rolled for transportation.

The hammock consists of a rigid rectangular frame comprised of side elements 10 and ends 11, upon which rests a mattress 12, having 50 a covering 14, and provided at one end with a pillow 15 which may be of any desired shape. Formed longitudinally in the side elements 10 are interior slots 16, to which are fitted the tenons 18, of transverse bars 19, to the inner side and centrally in the

length of which are secured straps 20 by means of which the mattress is suspended.

Formed transversely through the side members 10 are a plurality of apertures 22 with which are engageable pins 23, the same 60 passing through openings 24 formed in the tenons 18, so that the bars 19 may be adjusted longitudinally of the frame.

Supporting means are provided by posts 25 set rigidly in the ground and which are 65 reinforced by cables 26, secured at one end of the posts and at the other to pins 27 driven into the ground.

Attached to the top of the posts 25, are other cables 28, which pass through eyes 30, 70 set in the lower side of the frame end elements 11, so that the cables are guided thereby, their ends being engaged with eyes 32, fixed in the transverse bars 19 upon their outer sides.

In operation, the posts 25 having been rigidly driven into the ground so as to be firmly held therein and the cables 26 arranged so as to reinforce the same, the cables 28 are engaged with the upper end of the 75 post and passed through the eyes 30, below the frame elements 11 and engaged in the eyes 32, of the transverse bars 19, which may be adjusted along the side elements 10, so as to raise or lower the hammock or bed 80 as may be desired.

In the adaptions shown in Figs. 5 to 8 inclusive the hammock or bed is comprised of a mattress like formation comprising front body elements 35, the cushioning material being held in relative position by the tuft buttons 36 as is the filling in pillows 38, the mattress being covered by an impervious blanket 39 which may be engaged with the edges by snap fastener elements 40 attached to the inner side of the blanket, the other elements 41 being on the mattress as is clearly indicated.

Over the pillow 38 is a cover 42, preferably of rigid construction, which affords 100 protection from rain or snow or other material dropping from above.

To the ends of the mattress are rods 44, having near their ends, hooks 45, containing rings 46 in which are secured one end 105 of cables 48, their other converging ends being secured in rings or eyes 49 which pass over the head 50 of the posts 51 in such manner as to support the hammock and its occupant.

Secured to the sides of the posts 51 by means of bolts 53 are other posts 54, the same being set at an angle, so that in connection with the posts 51 as to form rigid supports for the weight which the hammock is to carry. In order to prevent the several posts from entering into the ground to a greater depth than is desired, washers 52 are secured to the lower ends of the several posts.

10 Thus the hammock may be quickly extended ready for use, or rolled compactly as is shown in Fig. 8, in which condition it may be readily transported.

Having thus described my invention what I claim as new and desire to secure by Letters Patent, is:—

1. In a hammock, the combination with a rectangular frame and a mattress supported thereby, of a pair of transverse bars slidably mounted interiorly of said frame, means for engaging said bars in an adjusted position, cables secured to said bars and means for supporting said cables.
2. In a hammock, the combination with a rigid rectangular frame and a covering engaged therewith, of a pair of supports arranged at the ends of said frame, cables secured to the upper end of said supports,

means for guiding said cables below the end elements of said frame, a pair of bars 30 mounted parallel to the end members and adapted to move longitudinally within said frame, means for securing said bars in an adjusted position and connections between said bars and said cables whereby said frame 35 may be adjusted.

3. In a hammock, the combination with a rigid rectangular frame and a pair of supporting posts arranged at the ends thereof, of longitudinal slots formed in the inner 40 surfaces of the adjacent side elements of said frame, transverse bars having tenons engageable within said slots, pins passing through said longitudinal frame elements and said tenons whereby the bars may be engaged 45 therewith, supporting cables secured at one end to said supporting posts and at their other ends to said transverse bars, and guides arranged upon the end elements of said frame for said cables.

In testimony whereof I affix my signature.

JOHN DREXLER.

Witnesses:

JOHN SEYMOUR,
T. J. HENINGSHAW.
